UNITED STATES PATENT OFFICE.

OSCAR ANDERSON, OF FORT WILLIAM, ONTARIO, CANADA.

RAIL JOINT AND CHAIR.

Specification of Letters Patent.

Patented Oct. 27, 1914.

1,115,153.

Application filed June 1, 1914. Serial No. 842,297.

To all whom it may concern:

Be it known that I, OSCAR ANDERSON, a citizen of Sweden, residing at Fort William, in the Province of Ontario, Canada, have invented certain new and useful Improvements in Rail Joints and Chairs, of which the following is a specification.

The present invention relates to rail joints and chairs, and its object is to provide such a device which possesses great strength, is of simple construction, and therefore cheap to manufacture, and can be easily and quickly assembled, there being no bolts or screws through the rail.

In the accompanying drawing is illustrated one embodiment of my invention, and Figure 1 shows a perspective view of the assembled device. Fig. 2 a top plan view, with the rail partly in section. Fig. 3 a plan view of the locking slide, and, Fig. 4 an enlarged transverse section along line 4-4 of Fig. 2.

At each place along the track where two rails abut, is placed the chair proper, or foundation plate 11, which is long enough to span at least three of the ties 10. On the under side, the foundation plate is reinforced by webs 12, placed so as not to interfere with the ties. Above each tie, the edge of the foundation plate is provided with a cut or recess 13 so as to give the spikes 14 a good hold and prevent displacement of the plate. A rail supporting member 15 extending the whole length of the foundation plate 11 is riveted, bolted or in any other manner, rigidly secured to, or made integral with the foundation plate 11. This member is preferably placed on the side of the rail 18 that faces outward on the track, and the supporting member is provided with an upright wall 16, abutting against the neck of the rail and with its upper edge fitting closely under the rail head so as to give firm support when a train passes over it. The bends of the supporting member 15 are reinforced as for instance, by flanges 17 to stiffen the construction. On the opposite side of the rails 18, I provide a guide plate 19, which is secured to the foundation plate in the same manner as the supporting member 15. The edge of its top flange 20, facing the rail, does however, not reach beyond the edge of the rail foot, and this flange 20 is raised above the upper face of the foundation plate 11 about twice the thickness of the rail foot at its edge. The vertical wall 21 connecting

the flange 20 with the base portion of the guide plate 19 runs at a slight angle to the axis of the rail, thus forming a tapered guide, that is, the distance between the wall 60 21 and the corresponding face 22 of the supporting member is wider at one end of the chair than at the other. The bends of the guide plate 19 also reinforce in the same manner as the supporting member and as 65 here shown, by means of webs 23.

A slide 24 with a horizontally wedge-shaped base portion of the same inclination as the guide wall 21 fits in the space between the rail and the guide plate. Similarly to 70 the supporting member 15, it is provided with an upright wall 25 which reaches up under the head of the rail, in order to sustain the weight of a passing train. Flanges 26 are also here provided for the purpose 75 of stiffening the slide. At each end of the slide 24, I provide a round or square hole 27 for a spike or bolt. This hole registers with corresponding ones in the top flange 20 and the foundation plate 11, and is, if spikes 80 are used, preferably located above one of the ties, but may, in case of bolts being used, be located between the ties. For the sake of adjustment, it might be well to provide a number of such bolt holes spaced 85 slightly apart.

The assembling of this device will be evident from the above description. Suffice it to say that after the two rails have been placed in the chair, the slide 24 is driven in 90 with its narrow end foremost from the wider end of the guide until it is tightly wedged between the rail and the guide wall 21. Finally, the spikes are driven in through the holes 27, thus securely locking 95 the slide in place and firmly holding the rails in the chair.

Obviously much time and labor will be saved in using this chair, as there are no holes to be drilled through the rail or the 100 sides of the chair, no bolts to fit and no chance of the chair opening or the device working loose, there being no bolts to tighten.

What I claim as new is:—

A boltless rail chair comprising a foundation plate, a side-support, a guide and a slide, said plate, support and guide forming a rigid construction; said side-support and said slide each having a thin upright member impinging against the head and shank of the rail and transverse flanges reinforcing

105

110

ing the upright member; said slide being provided with a horizontally wedge-shaped base portion, one side of which engages the foot of the rail and the other side impinging against and having the same inclination as the inner side of said guide; the guide having an overlapping member engaging the upper side of said base portion and transversely running reinforcing flanges; a pair of diagonally intersecting webs on the under side of said foundation plate between each

two ties, said webs forming distance pieces for the ties; an interlocking member engaging in suitable holes in said overlapping member, said wedge-shaped base-portion 15 and said foundation plate respectively.

In testimony whereof I affix my signature in presence of two witnesses.

OSCAR ANDERSON.
